CLAIM

The ornamental design for a playing card holder with stand, as shown and described.

DESCRIPTION

FIG. 1 is a front, left side perspective view of the playing card holder with stand, showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in an alternate configuration.

The broken lines in the figures illustrate portions of the playing card holder with stand that form no part of the claimed design.
